UNITED STATES PATENT OFFICE

HARLEIGH R. HOLMES, OF LITTLETON, COLORADO

ROTARY SNOWPLOW

Application filed April 11, 1931. Serial No. 529,447.

This invention relates to improvements in snowplows and has reference more particularly to an improved rotary snowplow for use in removing snow from the highway.

5 It is of great importance to the country that the main highways should be open to traffic at all times and in order to maintain them in open condition during the winter months it often becomes necessary to remove 10 great quantities of snow and to cut through heavy drifts. For the purpose of removing snow from highways, a large number of different devices including machines having rotors have been invented and used.

15 It is the object of this invention to produce an apparatus that shall be so constructed that it can be applied to an ordinary truck when it is to be used and which can readily be removed from the truck during the summer 20 time and stored so that the truck can be used for other purposes.

Another object of this invention is to produce a snow removing apparatus of a simple construction that can be manufactured at a 25 reasonable price and which will have a large capacity for removing snow.

Another object of this invention is to produce a snow plow of the rotary type in which the rotor does not require to be enclosed in a 30 housing and which will therefore require much less power to operate it than would be required if the usual housing were employed.

A still further object of this invention is, to produce a snow removing mechanism that 35 does not require any cutting edges to be forced into the snow for the purpose of directing the snow to the rotor, but which instead of such cutting edges and scoops, shall be provided with a planer cylinder that is 40 mounted for rotation about a horizontal axis and which is located directly to the rear of the rotor and operated in such a way that it scrapes the snow and ice from the pavement and throws it towards the rotor which then 45 carries it out over the sides of the road.

Another object of this invention is to produce a machine of the type referred to in which the rotor and the planer cylinder can be adjusted simultaneously towards and 50 away from the road surface and in which

they can also be adjusted relative to each other.

The above and other objects that may appear as this description proceeds are attained by means of a construction and an arrangement of parts that will now be described in detail, and for this purpose reference will be had to the accompanying drawings in which the preferred embodiment of the invention has been illustrated, and in which:

Fig. 1 is a side elevation of a truck showing the improved snow removing apparatus in place thereon;

Fig. 2 is a top plan view of the rear portion of the truck, showing the parts to a somewhat larger scale than in Fig. 1;

Fig. 3 is a section taken on line 3—3, Fig. 1;

Fig. 4 is a section taken on line 4—4, Fig. 3;

Fig. 5 is a section taken on line 5—5, Fig. 2; and

Fig. 6 is a view looking in the direction of arrows 6—6, in Fig. 1.

In the drawings the apparatus that forms the subject of this invention has been shown as secured to an ordinary truck chassis. The 75 side members of the chassis frame have been designated by reference numeral 1, the front wheels by reference numeral 2 and the rear wheels by reference numeral 3. The engine for operating the truck is located underneath the engine hood 4, but has not been shown because it forms no part of this invention. The truck is provided with the ordinary semi-elliptical springs 5 between the chassis frame and the axle. Secured to the truck 80 frame is another frame having side members 6 that are located above the members 1 and are secured to the latter by means of bolts 7. Connecting the rear ends of the side members 6 is an angle iron 8. This angle iron is 85 held in place by means of angle brackets 9 as shown in Fig. 4. Secured to the horizontal flange of the angle iron is a bearing 10 in which the shaft 11 is rotatably mounted.

Since the truck to which the apparatus that forms the subject of this invention is applied, is intended to travel in reverse when the snow removing mechanism is in operation, the end of the truck that is usually referred to as the rear end will be referred to as the front end 95 100

in this description. The rear end of shaft 11 extends into a gear casing 12 that contains the reversing gear mechanism. These gears are controlled by means of a lever 13. Since 5 the reversing gear can be of any standard design, it will not be described in detail, but it is to be understood that by means of this gear shafts 11 and 14 can be rotated in the same direction or in opposite directions as 10 may be desired. Shaft 14 is driven directly by one or more engines 15 and rotates in the same direction at all times. Secured to the forward end of shaft 11 are three rotors A, B and C. The rotors each comprise a circular 15 plate 16 that is secured to the shaft by means of a pin 17 or some other suitable means and extending radially from these plates are arms that have an angular cross section. The arms have been designated by reference numeral 20 18. The rotor indicated by letter A is the largest and is preferably provided with six arms that extend radially or substantially radially therefrom. The outer ends of the arms on rotor A are connected by means of 25 rods 19. The outer ends of the blades 18 on rotor B are also connected by means of rods 19 and this is also true with the rotor indicated by letter C. Rotors B and C are each provided with three arms, while rotor A, as above 30 explained, has six arms; but the exact number of arms is a matter of choice and is not a material feature of this invention. The assembly comprising the three rotors forms a conical rotor like that shown in the drawings 35 and the three rotors operate together each doing only a portion of the work. Owing to the fact that the snow is handled by means of three separate rotors, it is evident that the blades can be smaller than would be required 40 for a single rotor. By means of the reversing gear, the rotor assembly can be turned in either direction. Attention is called at this point to the fact that the rotor assembly is not enclosed in a housing in accordance with 45 usual practice, as this has been found to be unnecessary for the reason that when the machine is cutting its way through a snowdrift, the snow itself, forms a substitute for the casing and as soon as the blades reach a point 50 above the snowbank, the snow carried by the blades will be thrown outwardly by the centrifugal force, and therefore an enclosing casing or housing has been found to be unnecessary. 55 It is evident that if the machine constructed as above described is driven into a snowdrift with the rotors operating, it will cut a circular opening through the snow; but it is also evident that such an opening would be 60 unsatisfactory as it would leave a very deep layer of snow in front of the wheels of the truck, and the latter would therefore climb on the snow and raise the mechanism above the surface of the roadway to such an extent 65 that the clearing action would not be suffi-

cient to give the results desired. In order to clear the roadway to within a given distance of the surface thereof, the machine has been provided with a planer head that rotates on a shaft 20 which extends horizontally a short 70 distance above the roadway and between the truck and the rotor A. The planer head as now constructed consists of two angular members 21 that are held in place on the shaft 20 by means of bolts 22 or other equivalent means. Removable blades 23 are secured to members 21. Shaft 20 is journalled in bearings 24 and has one end provided with a bevelled gear 25. A shaft 26 carries a bevel pinion 27 that cooperates with the gear 25. 80 Shaft 26 extends diagonally upwards and has its upper end provided with a pinion 28 that cooperates with another pinion 29 that is carried by a shaft 30. Shaft 30 has a pinion 31 that meshes with a pinion 32 on shaft 33. 85 Pinions 31 and 32 are located within a housing 34 and the outer end of shaft 33 has a sprocket wheel 35. A sprocket chain 36 connects the sprocket gear 25 with a similar sprocket wheel 37 on shaft 14. The different 90 gears are so related to one another that the planer head will be rotated in a counterclockwise direction when viewed as in Fig. 1. The lower part of the planer blades will therefore move in the direction in which the 95 mechanism is travelling and will throw the snow and ice forwardly into the path of the rotor A which will carry the same out and throw it to the side of the road. The planer head is mounted in a frame that comprises 100 two vertical angle irons 38 that are each provided with a slot 39 through which a bolt 40 extends. The upper ends of the angle irons are provided with an outturned portion 41 to which the lower end of a screw 42 is connected. This screw passes through a threaded opening in a bracket 43 and when the screw is turned in either direction, the angle iron that is connected with it will be moved in a corresponding direction. The two screws 42 105 must be rotated substantially simultaneously, and may, if desired, be interconnected by means of a sprocket chain which has not been shown. Carried by the angles 38 is a plate 44 whose lower end is curved forwardly and downwardly and terminates at 45 which is substantially on the level with the shaft 20. Diagonal braces 46 are provided and these 110 support the back wall of the housing in which the planer head rotates. This rear wall consists of a plate 47 to the upper and lower edges of which angles 48 and 49 are respectively connected. Push rods 50 extend from the ends of the axle 51 to lugs or ears 52 carried by the rear wall of the housing in the manner shown in Figs. 1 and 4. The push rods hold the frame in position during the 115 operation of the machine. By turning the screws 42 the planer head can be adjusted 120 125 130

with respect to the road without altering the adjustment of the rotors.

For the purpose of simultaneously adjusting the rotors and the planer head with respect to the roadway, means has been provided for compressing the springs 5 so as to move the chassis frame towards and away from the roadway. The means for compressing the springs has been shown in Fig. 5 and consists of a hydraulic cylinder 53 that is mounted on a bracket 54 carried by the chassis frame 1. Located within the cylinder is a piston 55 and a piston rod 56 extends from the piston through the cylinder head 57 and is secured to its upper end to a cross head 58. Rods 59 extend downwardly from the ends of the cross head 58 and are connected with the plate 60 on top of the spring. A hydraulic pump 61 is provided for pumping oil into the cylinder below the piston. As the piston moves upwardly, the chassis frame will move downwardly due to the flexure of the spring. One hydraulic cylinder is provided on each side of the chassis frame and both of them are connected to the pump by means of pipes 62 and 63. The space above the piston can be utilized for storing the oil.

Located in front of each of the wheels 3 is an inclined blade 64 that serves to scrape the snow outwardly in front of the wheels and thereby prevent the wheels from climbing as they would otherwise do.

The machine above described is operated by moving it in the direction in which the propeller or rotor is pointing and the latter will therefore be forced against the snowdrifts and the several sections of the rotor will cut the snow and throw the same to the side of the roadway. As the machine moves forwardly the rotating planer head cuts the snow and ice adjacent the road surface and piles the same into a position where the lower ends of the blades on rotor A can catch them and remove them from the roadway. Any loose snow or ice is removed by means of the blades 64 and the wheels 3 therefore remain a certain distance from the surface of the roadway regardless of the thickness of the snowdrifts and after the machine has passed over the road the snow and ice will be removed to a given depth over the whole width of the roadway.

Particular attention is called to the fact that the rotors are not enclosed and that the construction is therefore much cheaper and simpler than if a housing were employed. Another feature of the construction that is of great importance is that the planer head can be adjusted with respect to the roadway independently of the rotor, while the two can be simultaneously adjusted when desired.

Attention is also directed to the fact that this machine can be applied to an ordinary truck and can be removed and stored during the summer time so that the truck can be

employed for other purposes, and in this way the investment is much smaller than where the snow removing mechanism is so constructed that it forms part of the truck for in the latter case the truck can be used for no other purpose and the entire investment is therefore left idle except for the few days in winter when it is needed.

Having described the invention what is claimed as new is:

1. A snowplow comprising, in combination, a truck, means for propelling the same, a rotor carried by the forward end of the truck and mounted for rotation about an axis parallel with the direction of travel and a planer head mounted for rotation about a transverse axis, said head lying between the rotor and the truck and directly above the roadbed and means for turning the head so that its lower part travels forwardly, the head having a plurality of planer blades.

2. A snowplow comprising, in combination, a truck, means for propelling the same, a rotor carried by the forward end of the truck and mounted for rotation about an axis parallel with the direction of travel, a planer head mounted for rotation about a transverse axis, said head lying between the rotor and the truck and directly above the roadbed, means for turning the head so that its lower part travels forwardly, the head having a plurality of planer blades and means for adjusting the planer head with respect to the road surface.

3. A snowplow comprising, in combination, a truck, means for propelling the same, a rotor carried by the forward end of the truck and mounted for rotation about an axis parallel with the direction of travel, a planer head mounted for rotation about a transverse axis, said head lying between the rotor and the truck and directly above the roadbed, means for turning the head so that its lower part travels forwardly, the head having a plurality of planer blades and means for simultaneously adjusting the planer head and the rotor towards and away from the road surface.

4. A snowplow comprising, in combination, a truck, means for propelling the same, a rotor carried by the forward end of the truck and mounted for rotation about an axis parallel with the direction of travel, a planer head mounted for rotation about a transverse axis, said head lying between the rotor and the truck and directly above the roadbed, means for turning the head so that its lower part travels forwardly, the head having a plurality of planer blades, means for adjusting the planer head with respect to the road surface and means for simultaneously adjusting the planer head and the rotor towards and away from the road surface.

5. An apparatus for removing snow from a roadway comprising, in combination, a self-

- propelled truck, a rotor carried by the truck and mounted for rotation about an axis that extends in the direction in which the truck travels, the rotor having a plurality of substantially radial blades whose length is somewhat less than the distance from the axis of rotation to the surface of the roadway, means for turning the rotor, means comprising a planer head provided with blades for removing snow from the top of the roadway, said planer head being located between the rotor and the truck and means for turning the planer head so that the lower part thereof rotates in the direction of travel.
6. An apparatus for removing snow from a roadway comprising, in combination, a self-propelled truck, a rotor carried by the truck and mounted for rotation about an axis that extends in the direction in which the truck travels, the rotor having a plurality of substantially radial blades whose length is somewhat less than the distance from the axis of rotation to the surface of the roadway, means for turning the rotor, a planer head carried by the truck at a point directly to the rear of the rotor, said head having a plurality of planer blades and mounted for rotation about an axis substantially perpendicular to the direction of travel and located a short distance above the roadway and means for turning the planer head in such a direction that the underside moves in the direction of travel.
7. An apparatus for removing snow from a roadway comprising, in combination, a self-propelled truck, a rotor carried by the truck and mounted for rotation about an axis that extends in the direction in which the truck travels, the rotor having a plurality of substantially radial blades whose length is somewhat less than the distance from the axis of rotation to the surface of the roadway, means for turning the rotor, a planer head carried by the truck at a point directly to the rear of the rotor, said head having a plurality of planer blades and mounted for rotation about an axis substantially perpendicular to the direction of travel and located a short distance above the roadway, means for turning the planer head in such a direction that the underside moves in the direction of travel and means for adjusting the position of the planer with respect to the surface of the roadway.
8. An apparatus for removing snow from a roadway comprising, in combination, a self-propelled truck, a rotor carried by the truck and mounted for rotation about an axis that extends in the direction in which the truck travels, the rotor having a plurality of substantially radial blades whose length is somewhat less than the distance from the axis of rotation to the surface of the roadway, means for turning the rotor, a planer head carried by the truck at a point directly to the rear of the rotor, said head having a plurality of planer blades, and mounted for rotation about an axis substantially perpendicular to the direction of travel and located a short distance above the roadway, means for turning the planer head in such a direction that the underside moves in the direction of travel and means for adjusting the position of the planer with respect to the surface of the roadway.
9. A device for removing snow from a roadway comprising, in combination, a self-propelled truck, a motor carried by the truck, a shaft mounted for rotation about an axis parallel with the direction of motion, means for rotating the shaft by power derived from the motor, a plurality of separate rotors secured to the shaft in front of the truck, the rotor nearest the truck being larger than the others and the rotor farthest from the truck being the smallest whereby a conical rotor assembly is produced, each rotor having a plurality of radial blades, a planer head carried by the truck, said cylinder being located between the rotor and the truck and mounted for rotation about a substantially horizontal axis perpendicular to the direction of travel, the head having blades and means for rotating the planer head in such a direction that the lower part thereof moves in the direction of travel.
10. A device for removing snow from a roadway comprising, in combination, a self-propelled truck, a motor carried by the truck, a shaft mounted for rotation about an axis parallel with the direction of motion, means for rotating the shaft by power derived from the motor, a plurality of separate rotors secured to the shaft in front of the truck, the rotor nearest the truck being larger than the others and the rotor farthest from the truck being the smallest whereby a conical rotor assembly is produced, each rotor having a plurality of radial blades, a planer head carried by the truck, said head being located between the rotor and the truck and mounted for rotation about a substantially horizontal axis perpendicular to the direction of travel, the head having blades, means for rotating the planer head in such a direction that the lower part thereof moves in the direction of travel and means for adjusting the position of the rotor and the planer head with respect to the roadway.

In testimony whereof I affix my signature. 120
HARLEIGH R. HOLMES.
